John Law Kerr, INVENTOR
BY Victor J. Evans & Co.

ATTORNEY

UNITED STATES PATENT OFFICE

JOHN LAW KERR, OF ALBANY, GEORGIA

SPIKE ATTACHMENT FOR SHOES

Application filed January 15, 1932. Serial No. 586,799.

This invention relates to shoe attachments and its general object is to provide an attachment with ground penetrating means, that can be easily and expeditiously detachably secured to ordinary shoes for use in playing golf and other purposes, where spiked shoes are necessary or desired.

A further object of the invention is to provide a spike attachment for shoes that is adjustable to fit shoes of various widths with the result it can be used with shoes of any size.

Another object of the invention is to provide a spike attachment for shoes that includes loss preventing means so that in the event the attachment should become detached from the sole, it will still be secured to the shoe and can be readily replaced on the sole.

A still further object of the invention is to provide a spike attachment of the character set forth, that is simple in construction, inexpensive to manufacture and extremely efficient in operation and service.

This invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:

Figure 1 is a perspective view illustrating one form of my present invention applied to a shoe.

Figure 2 is a similar view of a modified form.

Figure 3 is a perspective view illustrating one end of the attachment shown in Figure 1 and the manner of securing the loss preventing means to the shoe lace.

Referring to the drawing in detail, the letter A indicates a shoe of the usual construction, and the attachment as shown in Figures 1 and 3 includes a pair of cooperating wire members, each of which is formed from a single strand of wire. One of these

wire members is looped intermediate its ends as at 1, and thence extended into opposed portions 2 which are bent at right angles upon themselves as at 3 to provide ground penetrating means 4. From the right angle bent portions the wire member which is indicated by the reference numeral 5 is bent back upon itself to provide aligned portions 4' that have formed therewith parallel end portions 5' and these parallel end portions are bent to provide sole engaging fingers 6 that are adapted to grip the side and top of the sole as best shown in Figure 3.

The other wire member is indicated by the reference numeral 7 and is likewise looped intermediate its ends, as at 8, and thence is bent at right angles upon itself to provide ground penetrating means 9. From the ground penetrating means the wire is extended to provide parallel portions which are bent at their ends to form sole engaging fingers 10 that are adapted to grip the side and top of the sole as shown in Figure 1.

Received by the loops of each of the wire members 5 and 7 are rings 11 that are secured to the end convolutions of a coil spring 12, the latter being adapted to urge the wire members toward each other so that the spring fingers 6 and 10 set up a clamping engagement against the sole as clearly shown in Figure 3.

Secured to one of the rings is one of the end links of a chain 13, while the opposite end link of the chain has secured thereto one end of a flexible member 14, while the opposite end of said flexible member is adapted to be secured to the lace of the shoe as shown in Figure 3.

When it is desired to adjust the attachment to fit small size shoes, the rings 11 can be removed and in this event the end convolutions of the coil spring are secured directly to the looped portions of the wire members as will be apparent.

In Figure 2 I have illustrated a modified form of my invention and this form includes plates, one of which is indicated by the reference numeral 15, and the other by the reference numeral 16. The plate 15 is substantially V-shape and has formed therewith a

pair of spaced parallel upturned ears 17 to provide sole engaging means. These ears 17 are formed with the outer edge of the plate 15 while formed with the inner edge and at 5 the ends thereof are lugs 18, the latter providing ground penetrating means. The plate 15 is further provided with a tongue 19, and the plate 16 is provided with a similar tongue 20 and these tongues receive rings 21 that 10 are secured to the ends of a coil spring 22. The plate 16 is likewise substantially V-shape in configuration and includes upturned ears 23 and ground penetrating lugs 24. Formed with the plate 16 is an apertured ear 25 which 15 has one end link of a chain 26 secured thereto, while fixed to the opposite end link is one end of a flexible member 27 which is adapted to have its opposite end secured to the shoe lace as shown in Figure 3.

20 When it is desired to adjust the attachment as shown in Figure 2, the rings 21 may be removed, and the ends of the coil spring 22 is then secured directly to the tongues 19 and 20.

25 From the above description and disclosure of the drawing it will be obvious that I have provided a spike attachment capable of being secured to shoes of practically all sizes, and it is believed that the drawing clearly illustrates the manner of applying the attachment to a shoe, but it might be stated that the sole engaging means of one of the members in each form of the invention is disposed against the sole, thence the other member is arranged 30 against the sole and held accordingly through the instrumentality of the coil springs. The flexible members are then tied to the shoe laces in order to prevent loss of the attachments.

35 It is thought from the foregoing description that the advantages and novel features of my invention will be readily apparent.

40 I desire it to be understood that I may make changes in the construction and in the combination and arrangement of the several 45 parts, provided that such changes fall within the scope of the appended claim.

What I claim is:

45 A spike attachment for a shoe, comprising a pair of members each of which being formed 50 from a single strand of wire bent to provide an intermediate looped portion, ground penetrating means formed with said members, sole gripping means formed with said members, a coil spring having connection with the 55 looped portions of said members to urge the sole gripping means in operative position, rings for connecting the coil spring to the looped portions, and a flexible means having one end secured to one of said rings and its 60 opposite end being adapted to be secured to the lace of the shoe.

In testimony whereof I affix my signature.
JOHN LAW KERR.
